(57) CLAIM

The ornamental design for goggles, as shown and described.

DESCRIPTION

FIG. 1 is a perspective view of an ornamental design for goggles;

FIG. 2 is a top view thereof;

FIG. 3 is a front view thereof;

FIG. 4 is a perspective rear bottom view;

FIG. 5 is right side view thereof; and,

FIG. 6 is a left side view thereof opposite the right side view.
The broken line shown in FIGS. 1-6 at the end of the strap
which define the bounds of the claimed design form no part
thereof.
